DESIGN FOR A WRIST WATCH

Georges Croisier, Geneva, Switzerland

Application April 3, 1939, Serial No. 84,020
In Switzerland February 1, 1939

Term of patent 7 years

To all whom it may concern:

Be it known that I, Georges Croisier, a citizen of Switzerland, residing at Geneva, Switzerland, 27 Rue de la Coulouvrière, have invented a new, original, and ornamental Design for a Wrist Watch, of which the following is a specification, reference being had to the accompanying drawing, forming part thereof.

Figure 1 is a plan view of a wrist watch showing my new design, and Figure 2 is an elevational view thereof from the side of the winding crown.

I claim:

The ornamental design for a wrist watch, as shown.

GEORGES CROISIER.
